UNITED STATES PATENT OFFICE.

ORVIN E. MCQUEEN, OF OAKLAND, ILLINOIS.

SELF-SOAPING WASHBOARD.

1,267,245.

Specification of Letters Patent. Patented May 21, 1918.

Application filed May 8, 1917. Serial No. 167,261.

To all whom it may concern:

Be it known that I, ORVIN E. MCQUEEN, a citizen of the United States, residing at Oakland, in the county of Alameda and State of Illinois, have invented certain useful Improvements in Self-Soaping Washboards, of which the following is a specification, reference being had therein to the accompanying drawing.

- 10 The present invention has reference generally to improvements in that class of inventions known as laundry and more particularly relates to a self soaping washboard.
- 15 As the primary aim and object it is contemplated by this invention to so construct the rubbing plate of the washboard so that soap may be fed to the outer or rubbing surface of the rubbing plate whereby when
- 20 clothes are being rubbed thereover soap will be applied thereto during the rubbing action.

It is an equally important object of this invention to provide novel soap containing means mounted in the back part of the washboard so that soap contained in the receptacle will be arranged in communication with the outer surface of the rubbing plate.

As an additional object the present invention embraces the provision of novel 30 spring pressed follower means mounted in the receptacle for yieldingly holding the soap within the receptacle against the slots in the rubbing plate which establish communication between the outer surface of the 35 rubbing plate and the receptacle, the soap being held against the slots to prevent the passage of water therethrough while clothes are being rubbed on the rubbing plate.

More particularly, the present invention 40 consists in the provision of spring means of a novel construction for yieldingly holding the follower cover plate against the soap in the receptacle and for permitting of the removal of the plate when it is desired to refill 45 the receptacle.

It is a more specific object of the present invention to provide improved means for maintaining the soap receptacle in the backboard.

50 Among the other aims and objects of this invention may be recited the provision of a device of the character mentioned with a view to compactness, and in which the number of parts are few, the construction simple,

the cost of production low and the efficiency 55 high.

Other improvements and novel details in the construction and arrangement of the various parts of the apparatus will be brought out more in detail in the description 60 to follow, which for a clear understanding of the invention should be considered in connection with the accompanying drawings forming a part hereof, and wherein is disclosed for the purpose of illustration a convenient and satisfactory embodiment of the 65 invention. It is to be noted in this connection that minor changes in the construction and arrangement of parts may be made without departing from the spirit of the invention or the principle of operation of the 70 various parts.

The invention is clearly illustrated in the accompanying drawings, in which—

Figure 1 is a rear elevation of the improved washboard;

Fig. 2 is a front elevation thereof;

Fig. 3 is an enlarged fragmentary vertical section taken on line 3—3 of Fig. 1 in the direction in which the arrows point; and 80

Fig. 4 is an enlarged transverse section taken on line 4—4 of Fig. 1 in the direction in which the arrows point.

Similar reference characters are employed in all of the above described views to indicate 85 corresponding parts.

Referring, now, more particularly, to the accompanying drawings there is provided a washboard including a supporting frame and consisting of a top board 1 from the respective ends of which depend supporting side legs 2. A back board 3 is rigidly mounted between the supporting legs and is arranged in abutting relation with the top board being positioned adjacent the rear surface thereof and provided with a rectangular opening 4 for a purpose that will presently appear. The transverse bar 5 is mounted between the legs 2 adjacent the lower or outer ends thereof while a corrugated rubbing plate 6 has its respective ends secured to the front face of the backboard and to the transverse bracing bar 5. The upper end of the transverse corrugated rubbing plate 6 terminates in substantial alignment with the lower edge of the top board while the inner corrugated portions 7 are provided with elongated transverse slots 8.

These slots 8 establish communication with the opening 4 for a purpose that will presently appear. Vertically extending truss rods 9 have their respective ends connected 5 to the rear surface of the backboard, the transverse bar 5 being arranged vertically of the washboard and serving to brace the rubbing plate to prevent sagging thereof when in use.

10 With a view toward providing the improved means for supporting the soap so that it may be fed to the outer surface of the rubbing plate and applied to clothes as they are being moved over the rubbing plate in 15 the customary manner, a rectangular receptacle 10 is provided with an open bottom the side walls of the receptacle being arranged in close relation with the sides of the opening while ears 11 extend from the outer 20 edges of the receptacle and are anchored to the rear surface of the back plate by means of suitable fastening devices 12. The opening is of such a size as to effectively accommodate preferably two pieces of soap 13 25 which are inserted in the receptacle and arranged against the slotted inner portions 7 so that the soap will prevent leakage of water through the slots 8 as clothes are being rubbed over the plate 6 yet at the same 30 time owing to the relation of the pieces of soap the latter will be applied to the clothes during the rubbing action.

As intimated, improved means have been provided for yieldingly holding the pieces 35 of soap 13 against the slotted inner portions 7 of the corrugated rubbing plate 6. In reducing this feature of the invention to practice a follower cover plate or lid 14 is employed. This plate is of a rectangular configuration and has its outer edges arranged 40 in close relation with the inner surface of the receptacle 10 and is yieldingly held against the soap so as to consequently hold the soap yieldingly against the inner surface 45 of the rubbing plate by suitable resilient means. The resilient means in the present instance consist of coil springs which are preferably formed from single pieces of wire and embody securing portions 15 rigidly connected to the rear surfaces of the 50 legs by means of suitable fastening devices 16. The portions continuing from the securing portions are coiled as indicated by the numeral 17 while the outer ends 18 bear 55 against the outer faces of the cover plate 14 being preferably positioned in the short groove 19 in the rear surface of the plate. By this arrangement it will be appreciated that the springs besides serving to yieldingly hold the pieces of soap in position are 60 capable of being lifted upwardly to consequently permit of the removal of the cover

plate in order that fresh pieces of soap may be inserted in the receptacle when so desired.

In use, assuming that the parts have been assembled in the manner described it is only necessary to use the washboard in the customary manner, that is by dampening the clothes and rubbing them over the outer surface of the rubbing plate 6. Owing to the novel arrangement of the pieces of soap 13 which are yieldingly held against the inner slotted portions 7 of the plate 6 the application of soap to the clothes as the latter are being rubbed over the board is assured, thereby serving as a labor saving device.

It is thought that in view of the foregoing a further detailed description of the invention is entirely unnecessary. Likewise it is believed that the advantages of the invention will be readily apparent.

As many changes could be made in the above construction and many apparently widely different embodiments of this invention could be made without departing from the scope thereof, it is intended that all matter contained in the above description or shown in the accompanying drawings shall be interpreted as illustrative and not in a limited sense. It is also to be understood that the language used in the following claim is intended to cover all the generic and specific features of the invention herein described and all statements of the scope of the invention, which, as a matter of language might be said to fall therebetween.

Having thus fully described this invention, what is claimed as new and desired to be secured by Letters-Patent, is:—

A washboard of the character described consisting of a supporting frame including a back board having a rectangular opening therein, a corrugated rubbing plate the inner portions adjacent the upper end of which are provided with a plurality of transverse slots establishing communication with the opening, a rectangular soap containing receptacle snugly fitted in the opening in the back plate, ears projecting from the outer edges of the receptacle, means for anchoring the ears against the outer faces of the back board, a soap follower plate the outer edges of which are arranged in close relation with the walls of the receptacle, and coil springs the respective ends of which are secured to the rear surface of the supporting frame and bearing against the outer face of the follower plate so as to yieldingly hold the soap in the receptacle against the slots in the rubbing plate.

In testimony whereof I affix my signature.

ORVIN E. McQUEEN.
